UNITED STATES PATENT OFFICE

2,137,455

INTERNAL COMBUSTION ENGINE

Pietro Maniscalco, Toledo, Ohio

Original application January 11, 1937, Serial No. 120,021. Divided and this application July 14, 1937, Serial No. 153,582

3 Claims. (Cl. 123—72)

This invention relates to a new and improved internal combustion engine.

One of the objects of this invention is to provide certain improvements in an internal combustion engine which includes precompressing means and a channel connecting the same with the combustion cylinder, such improvements comprising a control valve provided in said channel and operating means connecting said valve with the 10 throttle valve on the carburetor, for synchronizing said valves to operate them in unison.

Another object of this invention is to provide a valve in the chamber which contains the pre-compressed fuel mixture prior to its entry to the combustion cylinder, also means whereby said valve is connected with the throttle valve on the carburetor, to be operated in unison therewith.

These and various other objects and advantages are attained with this invention, as will 20 become apparent from the following description, taken in connection with the accompanying drawings in which the invention is shown in its preferred form of construction, it being understood that various other arrangements and forms may 25 be resorted to for carrying out the objects and purposes of this invention.

In the drawings:

Fig. 1 is a side elevational view of my invention in its preferred form of construction, parts 30 being broken away.

Fig. 2 is an end elevational view thereof, partly in section, taken on line 2—2 of Fig. 1.

Fig. 3 is a top plan view thereof.

This is a division of my prior application for 35 patent for Combination gasoline and oil engine, Serial Number 120,021, filed Jan. 11, 1937.

In the drawings this invention is illustrated in its preferred form of construction, embodied in an internal combustion engine which is adapted to 40 utilize as its fuel, gasoline and also different types and grades of oil. This construction illustrated comprises a combustion cylinder 11 containing a piston 12 therein, and a supercharging or precompressing cylinder 13 containing a piston 14 therein, and whereby the fuel mixture is compressed and preheated. A chamber 15 operatively connects the two cylinders and is adapted to store and to convey a required amount of precompressed fuel mixture from cylinder 13 45 to cylinder 11, at proper temperature and pressure to provide a full power stroke of piston 12. Cooling jackets 16 are provided around the cylinders and communicate with a cooling jacket 17 provided around chamber 15, while a hot water return pipe 18 conducts the hot water from

said jacket to a suitable radiator, an inlet for the water to the cooling jacket being similarly provided.

A carburetor 20 has a neck 21 connected with the intake end 22 of the intake manifold 22, and has an air intake and filter member 23 connected to it by a conduit 24. A control valve 25 is provided in neck 21 and is operated by a crank lever 26 mounted on the valve stem and by an operating rod 27 extending from the lever. From 10 said manifold 22 the pre-mixed fuel charge passes thru the branch conduits 28 into the entrance chambers 29 provided at the upper ends of the several cylinders 13. A valve element 30 closes the valve seat on each cylinder 13 and descends 15 to admit the fuel mixture from the chamber 29 into the cylinder.

The means provided for operating these valves includes a spring 31 on the outer end of each valve stem 32 adapted to urge the valve 30 to its 20 closed position, when the down stroke of piston 14 is completed. For closing these valves a rocker arm 33 is pivoted on a bracket 34 on the cylinder housing, and a rocker shaft 35 bears against the end 33' of arm 33 to depress stem 32 and open 25 valve 30. Shaft 35 extends into the crankcase 36 and is actuated by a cam 37 on a cam shaft 38 which is driven thru an attached gear 39 (see Fig. 3) actuated by a gear 40 mounted on one end of a crank shaft 41 which carries the flywheel 30 42 on its other end.

A valve 43 on a stem 44 is urged by a spring 45 to the closed position on its valve seat, thereby closing communication between cylinder 13 and chamber 15. Valve 43 is thereby held closed 35 during the main upward stroke of piston 14, so that the mixture in cylinder 13 will be properly compressed, and the valve will open when the proper pressure of the mixture is reached. The preheated and precompressed fuel mixture then 40 enters chamber 15, and at the end of the upward stroke of piston 14 the valve 43 is closed by spring 45, and the mixture is confined in chamber 15.

A valve 46 closes the valve opening provided at the upper end of cylinder 11, to close communication between said cylinder and chamber 15. Said valve 46 is held closed by a spring 47 on a stem 48, until the stem is actuated by an opening mechanism which includes the cam 49 on a cam shaft 50, adapted to actuate a stem 51 50 adjustably connected to a rod 52 of which the upper end actuates a lever 53 pivoted at 54 on a bracket 55 provided on the cylinder casing. The free end of lever 53 bears on valve stem 48 to open valve 46 against the action of spring 47, at 55

the proper time for the admission of the fuel mixture to combustion cylinder 11, thru the operation of rod 52, cam 49, shaft 50 and a gear 51 thereon, driven by means of a gear 56 on 5 crank shaft 41.

An exhaust port 59 is provided in the peripheral wall of cylinder 11, and communicates thru a branch conduit 60 with exhaust manifold 61. This port 59 and the operating mechanism for 10 valve 46 are arranged and timed so that the valve starts opening before exhaust port 59 is fully uncovered, thereby assisting the piston in clearing dead gases from said cylinder 11. When port 59 is closed by piston 12 during its upward stroke, 15 then combustion cylinder 11 will be filled with a clean fuel mixture fed from chamber 15; whereupon lever 53 raises from stem 48 and spring 47 closes valve 46. Piston 12 then completes its upward stroke and the compressed mixture is fired 20 by the action of a spark plug 62 mounted in the upper end of the cylinder, piston 14 being forced downward until it clears exhaust port 59 and the burnt gas is ejected into exhaust manifold 61.

A piston rod 64 is pivoted to piston 12 and to 25 a crank 65 on crank shaft 41, and a piston rod 66 is pivoted to piston 14 and to an arm 67 offset laterally from rod 64, thereby providing a definite advance of stroke of the supercharging piston 14 relative to the main piston 12.

30 A safety valve is preferably also provided for chamber 15. This comprises a bypass 68 provided in the top part of cylinder 13, connecting chamber 15 with chamber 29, said bypass being closed by a valve 69 urged by a spring 70. The 35 tension of this spring and the action of this valve are adjustable, by operating an adjusting nut 71, so that the valve will open to pass fuel mixture from chamber 15 back to chamber 29 when the pressure in chamber 15 becomes excessive.

As more fully disclosed and claimed in the above identified parent case, the means provided for utilizing the hot exhaust gases for preheating the heavy fuels or oils includes fuel conducting 45 means mounted in the exhaust manifold 61, the fuels being supplied thereto by pipes 73 and 74; while from said conducting means the fuel is conveyed thru a conduit 75 to a T-connection 76 which is threaded on the float chamber 77, a supply pipe 78 being attached to said T-connection 50 for supplying gasoline directly therethru to the float chamber. Said float chamber 77 is connected to and is preferably made integral with the carburetor 20, by means of a neck 79 having 55 a fuel supply channel 79' extending therethru.

A cooling jacket 81 is mounted around the carburetor and float chamber, having its upper end connected thru an inlet tube 83 with the hot water return pipe 18 of the engine, and thru an 60 outlet tube 84 with the water jacket of the engine. The water from the engine jacket will thus circulate thru this jacket 81 and serve to maintain the temperature of the fuel fairly constant.

65 A control valve 85 is provided in each storage chamber 15 for definitely controlling the flow of fuel therethru to the combustion cylinder 11; and means is further provided for synchronizing the several control valves 85 of the several combustion cylinders 11 with the control valve 25 on the carburetor. This means preferably includes a rocker shaft 86 mounted on brackets 87 on the engine and having an arm 86' connected to a link 88 which is pivoted to a crank arm 89 provided 75 on crank lever 26 of the carburetor control valve

25. Links 91 are connected to arms 92 provided on said shaft 86 and to arms 93 extending from the stems of the several control valves 85. Thus, upon operating the rod 27 of the throttle valve 25, the several control valves 85 will be operated 5 in unison along with the throttle valve.

The usual choke valve 94 is provided in the air inlet channel 24 on the carburetor, being operated in the usual manner, by a rod 95 extending from the arm 96 on said valve. 10

I claim:

1. In an internal combustion engine, a plurality of combustion cylinders and a supercharging cylinder for each, a charge storing and conveying chamber connecting a combustion cylinder with its supercharging cylinder, a rotary valve in each chamber for controlling the flow of fuel mixture therethru to the combustion cylinder, a carburetor and an intake manifold connecting it with the several supercharging cylinders, a valve on the carburetor provided with means for manually operating it to control the flow of fuel mixture therefrom to the intake manifold, a rocker shaft on the engine and also arm and link means operatively connecting it with the several chamber valves, and means connecting said rocker shaft with the carburetor valve and its operating means, whereby to synchronize said valves and control manually in unison the flow of fuel mixture to the several supercharging cylinders and also therefrom to the combustion cylinders. 15 20 30

2. In an internal combustion engine, a plurality of combustion cylinders and a supercharging cylinder for each, a charge conveying chamber connecting a combustion cylinder with its supercharging cylinder, a spring-held valve between a chamber and its supercharging cylinder and a tappet valve between the chamber and its combustion cylinder, a carburetor and an intake manifold thereon and channel means connecting the latter with the several supercharging cylinders, a tappet valve between each channel and its cylinder, cam means operatively connected for operating the two sets of tappet valves, a 45 manually operated rotary valve on the carburetor and a rotary valve in each chamber, and means connected with said several rotary chamber valves and with said rotary carburetor valve, whereby to operate manually all of said rotary valves in unison. 40 45 50

3. In an internal combustion engine, a plurality of combustion cylinders and a supercharging cylinder for each, a charge conveying chamber connecting a combustion cylinder with its supercharging cylinder, a control valve in each chamber, a spring-held valve leading from each supercharging cylinder into its chamber, a tappet valve leading from each chamber into its combustion cylinder, a carburetor having a manually operated throttle valve and being adapted to utilize gasoline and oil for fuel and provided with a pair of supply pipes therefor, an intake manifold on the carburetor and provided with channels leading to the several supercharging 65 cylinders, a tappet valve leading from each channel into its supercharging cylinder, two sets of cams and cam shaft means for operating the two sets of tappet valves, cooperating gear means for actuating said cams and thereby said tappet 70 valves, and rod and link means connected with said control valves and with said throttle valve, whereby they are operable manually in unison. 60 65 70 75 80 85 90 95
